CLAIM

The ornamental design for a support for plant pot holders or the like, substantially as shown and described.

DESCRIPTION

FIG. 1 is a perspective view of a support for plant pot holders or the like showing my new design;
FIG. 2 is a side view thereof, both sides being identical;
FIG. 3 is a front view thereof, the rear being identical;
FIG. 4 is a top view thereof;
FIG. 5 is a bottom view thereof.
